UNITED STATES PATENT OFFICE.

LOUIS CHOLLET, OF PARIS, FRANCE, ASSIGNOR TO COMPAGNIE INDUSTRIELLE ET COMMERCIALE DU CYCLE ET DE L'AUTOMOBILE, OF PARIS, FRANCE.

PNEUMATICALLY-OPERATED HORN.

Application filed February 1, 1926, Serial No. 85,309, and in France April 6, 1924.

The present invention relates to improvements in pneumatically operated horns of the type described in copending application Serial No. 7,566 filed Feb. 9, 1925, and aims to simplify and perfect the construction and operation of such devices.

The various novel features of the invention are illustrated in the accompanying drawing in which:—

10 Figure 1 is a partial longitudinal section through the horn.

Figure 2 is a plan taken on line $x-x$.

Figure 3 is a plan taken on the lines $y-y$ in the direction of the arrows.

15 The horn consists of a bulb P connected to conduit 1, which terminates in a cover member designed to screw onto body portion 3 having prolongations 6 and 7 cooperating with the flared horn portion 8. Part 6
20 is screwed onto a suitable mounting on the automobile. Member 2 constituting an air outlet tube extends into body portion 3 and thus reduces its capacity.

Near the bottom of the inner portion of member 3 there is provided an annular shoulder portion 14 cut so as to have a slightly reentrant angle. Membrane 15 is supported by arms 15' on shoulder 14.

30 Arms 15' are formed by portion 15" cut out of the periphery of the membrane 15, said cut out portions forming passages for air to the bottom of the membrane. Membrane 15 is held in position by the cupel-shaped air distributing member 17 having an angle 18 corresponding to the angle of shoulder 14; 17 is held against membrane 15 by annular shoulder 5 when cover portion 2 is screwed down onto the body 3. Member 17 is provided with a series of holes 20 to 40 permit air to pass to the upper and lower surfaces of membrane 15.

The inner end 10 of tube 7 is arranged to project inwardly slightly below the level of shoulder 14 so that it does not touch membrane 15. It will be seen that in the appa-

ratus, as thus designed, the volume of the vibrating air chambers immediately above and below membrane 15 is quite small.

In operation, air from bulb P or other suitable source passes through conduit 1 into the small air chamber formed by cover 2, traverses holes 20 and passes under the membrane 15 through passages 15''. The streams of air passing to both sides of the membrane vibrates this member in the manner described in copending application Serial No. 7,566. 55

Having now particularly described and ascertained the nature of my said invention and in what manner the same is to be performed, I declare that what I claim is:

1. A device of the class described comprising in combination an air supply conduit, an air chamber communicating therewith, a partition dividing said chamber into two compartments, said partition comprising a circular membrane having peripheral recesses therein and an air distributing disc co-acting with said membrane and having perforations concentric with the orifices in the membrane, and an air outlet tube communicating with the air chamber. 65 70

2. A device of the class described comprising in combination a hollow cover member having an annular internal shoulder therein, a hollow body member coacting with the hollow member and having an annular internal shoulder therein, a circular membrane having peripheral recesses therein, an air distributing disc having a concave face and having perforations therein concentric with the recesses in the membrane, means for clamping said membrane and said air distributing disc between the annular internal shoulders of the body and of the cover member respectively, and an air outlet tube communicating with the hollow body member. 75 80 85

In testimony whereof I affix my signature.

LOUIS CHOLLET.
